UNITED STATES PATENT OFFICE.

FREDERIC C. ZEH, OF SAN FRANCISCO, CALIFORNIA.

WINDOW.

Application filed August 5, 1924. Serial No. 730,257.

To all whom it may concern:

Be it known that I, FREDERIC C. ZEH, a citizen of the United States, residing in the city and county of San Francisco and 5 State of California, have invented a new and useful Improvement in a Window, of which the following is a specification.

My invention relates to improvements in windows wherein a substantially invisible 10 screen is projected into the space between a pivotally mounted window and the casement when said window is partially opened.

The primary object of the present invention is to provide a new and improved window. 15

Another object of the invention is to provide a new and improved pivotally mounted window sash arranged to automatically screen a space between said window sash 20 and the casement when said sash is partly open, in any one of several open positions.

A further object of the invention is to provide a new and improved device of the character described wherein the screen is 25 concealed and invisible when the sash is closed and inconspicuous when the sash is partly open.

A still further object is to provide an improved window of the type set forth which 30 may be easily tilted upon its pivotal point to move the sash inwardly and into an apartment whereby a space may be provided at the top of said sash for ventilation purposes, and to automatically screen the 35 space between the upper portion of said sash and the casement.

A further object is to provide improved 40 means for closing the space between the sides of the window sash and the casement when the sash is partly open in order to prevent drafts and the entrance of rain, dust and other débris.

It is also an object to provide a sash of 45 the type set forth wherein said sash is pivotally mounted to the casement by means of a hinge adapted to prevent the entrance of rain, dust and other débris in other words that a weather-proof fit may be had between the sash and casement.

50 I accomplish these and other objects by

means of the preferred form of the improved device disclosed in the drawings forming a part of the present specification wherein like characters of reference are used to designate similar parts throughout the 55 said specification and drawings, and in which—

Fig. 1 is a partly broken inside elevation of my improved window, including the 60 sash;

Fig. 2 is a partly broken vertical sectional view of Fig. 1 showing the sash in a closed position in full lines and in partly open positions in dotted lines;

Fig. 3 is an enlarged, broken sectional detailed view of the manner in which a 65 weather-proof pivotal connection is obtained between the sash and casement; and

Fig. 4 is a broken side elevation of a portion of the pivotal hinge of said sash. 70

Referring to the drawings the numeral 1 is used to designate in general a window casement having a top pocket 2 and side pockets 3 formed adjacent preferably the top and side edges of the sash aperture of 75 said casement 1. An abutment or shoulder 4 is provided above the pocket 2, the purpose of which will hereinafter be more fully set forth.

Attached in any suitable manner to the 80 sill 6 of the casement 1, by means of a rectangular extension 7, is a round bead 8 extending across one edge of the sash aperture of said casement 1.

Pivotedly mounted upon said round bead 85 8 is a bead engaging member 9 formed preferably of sheet metal and arranged to closely engage and ride upon the periphery of the round bead 8. The member 9 is provided upon the upper portion thereof with 90 a longitudinally disposed web 11 provided with suitable apertures or holes 12.

The sash 15 has formed on the bottom edge thereof a longitudinally disposed semi-circular socket 12' arranged to engage the 95 round portion of the bead engaging member 9 and also a longitudinally disposed groove 14 arranged to engage the web 11 of the member 9. When the socket 12' and groove 14 are engaged with their respective 100

members a screw 16, or other suitable member such as a pin or rod, not shown, is inserted through the lower portion of the sash 15 and the holes 12 in the web 11 of the bead engaging member 9, whereby said sash 15 may be detachably connected to the bead engaging member 9 to facilitate placement and removal of the sash 15.

The upper end of the sash 15 is provided with a horizontally disposed screen section 17 which has one edge connected to the upper edge of and extends entirely across the said sash 15, said screen section 17 being arranged to be moved into and out of the pocket 2 in the upper portion of the casement 1 when the sash 15 is closed and opened, as disclosed in full lines and dotted lines, respectively, in Fig. 2 of the drawings.

When the sash 15 is partly opened as disclosed in Fig. 2 of the drawings the screen 17 is extended from the top of the said sash 15 to the casement thereby screening the space between the upper edge of said sash 15 and said casement 1 in such a manner and position that the said screen 17 is inconspicuous. And when the sash 15 is closed the screen 17 is moved into the pocket 2 of the casement 1 and the upper end or edge of the said sash abuts against the shoulder 4 and thereby effectively closes the entrance to said pocket 2 and the screen 17 is therefore concealed and invisible.

In order to prevent side drafts through the triangular space between the side edges of the sash 15 and casement 1 when said sash is partly open I have provided suitable wings 18 which may be of wood or any other suitable material, and these wings 18 are likewise arranged to be moved into and out of their respective pockets 3 on each side of the casement 1 when the sash is closed or opened. These wings 18 may be secured to the side edges of the sash 15 in any suitable manner.

In operation, the casement is provided with three pockets arranged on three sides of the window or sash aperture therein and the sash 15 is pivotally mounted on the fourth side by means of a suitable waterproof hinge or pivot. When the sash 15 is closed the screen 17 and wings 18 are invisible and concealed within their respective pockets 2 and 3. When the sash 15 is partly opened as disclosed in dotted lines in Fig. 2 of the drawings, the said screen 17 and wings 18 are partly withdrawn from their respective pockets to cover the space between the said sash 15 and casement 1. As the sash 15 is pivotally mounted to open forwardly from the top it is evident that the screen 17 will be at the top open space when the sash is partly opened, and the

side spaces between the said sash 15 and the casement 1 are effectively closed by the wings 18 so that ventilation may occur at the upper portion of the apartment and fresh air may enter said apartment through said screen. 70

As the open portion or space between said sash 15 and casement 1 is within the apartment it is obvious that no rain may enter through the screened space.

An adjustable fastening device 19, of any suitable type, is provided to hold the sash 15 securely in a closed or any one of several open positions.

The sash 15 may be lowered or moved upon its pivotal point to bring the said sash into a substantially horizontal position whereby the outer side of the window may be rendered readily accessible for cleaning or other purposes.

The sash 15 may be easily and readily detached for repairs or other reasons by removing the screws 16 which will disconnect the sash 15 from the web 11 of the bead engaging member 9. Then the sash may be easily lifted from engagement with said web 11 by opening sash 15 a sufficient amount to permit the same to be raised from said web.

While I have disclosed two sashes 15 in the casement 1 it is obvious that one or several sashes, according to the length of the window, may be used. It is equally obvious that the sash 15 may be pivotally mounted upon a vertically disposed bead without departing from the spirit of the invention.

Having thus described my invention what I claim as new and desire to secure by Letters Patent is—

1. The combination with a window casement having a pocket formed on one side of the window aperture therein, of a window sash hingedly mounted within said casement on the side opposite said pocket; and a screen section connected to the side of said sash adjacent said pocket and arranged to move into and out of said pocket when said sash is closed and opened, and to screen the space between said sash and casement when said sash is partly opened. 105

2. The combination with a window casement having a horizontal pocket formed in the upper side of the sash aperture of said casement, of a sash hingedly connected to said casement at its lower end and opposite the pocket in said casement; and a screen connected to the upper side of said sash and arranged to move into and out of said pocket when the window sash is closed and opened, and to screen the space between the top of said sash and the casement when said sash is partly opened. 120

3. The combination with a window case-

ment having a horizontal pocket formed in the upper side of the sash aperture of said casement, of a sash hingedly connected to said casement at its lower end and opposite the pocket in said casement; and a screen connected to the upper side of said sash and arranged to move into and out of said pocket when the window sash is closed and opened, and to screen the space between the top of said sash and the casement when said sash is partly opened; and means for locking the sash in a closed and several open positions.

4. The combination with a window casement having a horizontal pocket formed in the upper side of the sash aperture of said casement, of a sash hingedly connected to said casement at its lower end and opposite the pocket in said casement; and a screen connected to the upper side of said sash and arranged to move into and out of said pocket when the window sash is closed and opened, and to screen the space between the top of said sash and the casement when said sash is partly opened; and wings arranged to close the side spaces between said sash and casement when said sash is partly open.

5. The combination with a window casement having a horizontally disposed pocket adjacent the upper end of the sash aperture of said casement, of a sash hingedly connected to said casement on the lower edge of said sash; a screen connected to the upper end of said sash and arranged to move into and out of said pocket when the sash is closed and opened and to screen the space between the upper edge of said sash and the casement when the sash is partly open; and wings connected to the side edges of the sash and arranged to close the space between the sash and casement when said sash is partly opened.

6. The combination with a window casement, having a pocket formed adjacent one side of the sash aperture therein, of a round bead mounted within said casement and directly opposite said pocket; a sash having a longitudinally disposed groove hingedly engaging the bead to form a weather-proof hinge between one edge of said sash and the casement; and a screen connected to the opposite side from the hinge of said sash and arranged to move into and out of the aperture in the casement when the sash is closed and opened, and to screen the space between that edge of said sash and the casement when said sash is partly opened.

7. The combination with a window casement having a pocket formed adjacent one side of the sash aperture therein, of a round bead mounted within said casement and directly opposite said pocket; a sash having a longitudinally disposed groove hingedly engaging the bead to form a weather-proof

hinge between one edge of said sash and the casement; and a screen connected to the opposite side from the hinge of said sash and arranged to move into and out of the aperture in the casement when the sash is closed and opened, and to screen the space between that edge of said sash and the casement when said sash is partly opened; and means for securing the sash in a closed and several partly open positions.

8. The combination with a window casement having a pocket formed adjacent one side of the sash aperture therein, of a round bead mounted within said casement and directly opposite said pocket; a sash having a longitudinally disposed groove hingedly engaging the bead to form a weather-proof hinge between one edge of said sash and the casement; and a screen connected to the opposite side from the hinge of said sash and arranged to move into and out of the aperture in the casement when the sash is closed and opened, and to screen the space between that edge of said sash and the casement when said sash is partly opened; and wings secured to the sides of the sash adjacent the screen and arranged to close the space between said sash and the casement when said sash is partly open.

9. The combination with a window casement having pockets arranged on three sides of the sash aperture therein, of a sash hingedly connected to the fourth side of said aperture; wings mounted upon two sides adjacent the hinge side; and a screen connected to the remaining side of said sash, said wings and screen being arranged to move into and out of the pockets when the sash is closed or opened to close the space between said sash and casement when said sash is partly open.

10. The combination with a window casement having pockets arranged on three sides of the sash aperture therein, of a sash hingedly connected to the fourth side of said aperture; wings mounted upon two sides adjacent the hinge side; and a screen connected to the remaining side of said sash, said wings and screen being arranged to move into and out of the pockets when the sash is closed or opened to close the space between said sash and casement when said sash is partly open; and means for securing the sash in a closed or several open positions.

11. The combination with a window casement of having a pocket arranged adjacent one edge of the sash aperture in said casement; a round bead secured on the opposite edge of said aperture; a sash having a socket formed in one edge thereof to engage the bead to form a weather-proof hinge between said sash and casement; a screen mounted upon the opposite edge of the sash and arranged to move into and out of said

2
pocket when said sash is closed and opened and to close the space between said sash and casement when the sash is partly open.

12. The combination with a window casement having a pocket arranged adjacent one edge of the sash aperture in said casement; a round bead secured on the opposite edge of said aperture; a sash having a socket formed in one edge thereof to engage the bead to form a weather-proof hinge between said sash and casement; a screen mounted upon the opposite edge of the sash and arranged to move into and out of said pocket when said sash is closed and opened and to close the space between said sash and casement when the sash is partly open; and wings mounted upon the side edges of the sash adjacent the screen and arranged to close the side spaces between the sash and casement when the said sash is partly open.

13. The combination with a window casement having pockets arranged on three adjacent sides of the sash aperture in said casement; a round bead mounted upon the remaining side of the aperture; a bead engaging member pivotally mounted upon said bead; a sash having a longitudinally disposed socket in one edge thereof to engage the bead engaging member whereby a weather-proof hinge may be provided between the sash and casement; a screen mounted upon the opposite edge of the sash and arranged to be moved into and out of the central pocket of the casement when the sash is closed and opened; and wings mounted upon the remaining sides of the sash and arranged to be moved into and out of the remaining pockets of the casement when the sash is closed and opened, said wings and screen being arranged to close the space between the sash and casement when said sash is partly open.

14. The combination with a window casement having pockets arranged on three adjacent sides of the sash aperture in said casement; a round bead mounted upon the remaining side of the aperture; a bead engaging member pivotally mounted upon said bead; a sash having a longitudinally disposed socket in one edge thereof to engage the bead engaging member whereby a weather-proof hinge may be provided between the sash and casement; a screen mounted upon the opposite edge of the sash and arranged to be moved into and out of the central pocket of the casement when the sash is closed and opened; and wings mounted upon the remaining sides of the sash and arranged to be moved into and out of the remaining pockets of the casement when the sash is closed and opened, said wings and screen being arranged to close the space between the sash and casement

when said sash is partly open; and means for locking the sash in a closed and several open positions.

15. The combination with a window casement having a pocket arranged adjacent one edge of the sash aperture therein; a round bead secured to the opposite edge of said aperture; a bead engaging member pivotally mounted upon said bead; a sash having a longitudinal socket for engaging the bead engaging member; means for detachably connecting the sash with the sash engaging member; and a screen mounted on the opposite side of the sash from the bead and arranged to move into and out of the pocket in the casement when the sash is closed and opened and to close the space between that edge of the sash and the casement when the said sash is partly open.

16. The combination with a window casement having a pocket arranged adjacent one edge of the sash aperture therein; a round bead secured to the opposite edge of said aperture; a bead engaging member pivotally mounted upon said bead; a sash having a longitudinal socket for engaging the bead engaging member; means for detachably connecting the sash with the sash engaging member; and a screen mounted on the opposite side of the sash from the bead and arranged to move into and out of the pocket in the casement when the sash is closed and opened and to close the space between that edge of the sash and the casement when the said sash is partly open; and means for securing the sash in any one of several open positions.

17. The combination with a window casement having a pocket arranged adjacent one edge of the sash aperture therein; a round bead secured to the opposite edge of said aperture; a bead engaging member pivotally mounted upon said bead; a sash having a longitudinal socket for engaging the bead engaging member; means for detachably connecting the sash with the sash engaging member; and a screen mounted on the opposite side of the sash from the bead and arranged to move into and out of the pocket in the casement when the sash is closed and opened and to close the space between that edge of the sash and the casement when the said sash is partly open; and means for closing the side spaces between the sash and casement and adjacent the screen when said sash is partly open.

18. The combination with a window casement having a pocket arranged adjacent one edge of the sash aperture therein; a round bead secured to the opposite edge of said aperture; a bead engaging member pivotally mounted upon said bead; a sash having a longitudinal socket for engaging the bead engaging member; means for detachably connecting the sash with the sash engaging member; and a screen mounted on the opposite side of the sash from the bead and arranged to move into and out of the pocket in the casement when the sash is closed and opened and to close the space between that edge of the sash and the casement when the said sash is partly open.

ably connecting the sash with the sash engaging member; and a screen mounted on the opposite side of the sash from the bead and arranged to move into and out of the pocket in the casement when the sash is closed and opened and to close the space between that edge of the sash and the casement when the said sash is partly open; and wings

secured to the edges of the sash adjacent the screen edge, said wings being arranged to close the side spaces between the sash and casement when said sash is partly open.

In witness whereof I hereunto set my signature.

FREDERIC C. ZEH.
